COMBINED ANIMATED AND CHANGEABLE SIGN

Filed Nov. 19, 1930

UNITED STATES PATENT OFFICE

REN M. ANDERSON, OF CINCINNATI, OHIO

COMBINED ANIMATED AND CHANGEABLE SIGN

Application filed November 19, 1930. Serial No. 496,686.

My invention relates to illuminated signs, and its object is to afford an animation or changeable appearance in such signs by very simple means economically produced on a commercial scale, as well as, by equally simple means, to make such a sign changeable as to a part of its display, so that the attractiveness of the animated sign may be had in a sign adapted to have part of its display altered in accordance with changes in the business advertised, or for the sake of variety, whereby the animation and the changeability are mutually helpful toward the general object of effective advertisement.

I accomplish the above objects by the device illustrated, for example, in the accompanying drawing, in which—

Figure 1 is a front view of a sign in one stage of its operation;

Fig. 2 is a similar view of the same in its next stage of operation;

Fig. 3 is a diagrammatic horizontal cross section affording a comprehensive disclosure of the arrangement of the various elements of the sign, their respective parts of the display matter, and the lighting means, the section being on a plane corresponding to that of the line 3—3 of Fig. 2;

Fig. 4 is a partial vertical section on the plane of the line 4—4 of Fig. 2, with the thicknesses of the elements and the display matter thereon much exaggerated for clearness;

Fig. 5 is a rear view of the front display element;

Fig. 6 is a rear view of the rear display element;

Fig. 7 is an enlarged front view of the lower portion of the front display element, parts being broken away and omitted for lack of space;

Fig. 8 is a fragmentary view of the same, showing a modification; and

Fig. 9 is a similar view showing another modification.

In my Patent No. 1,737,290, issued November 26, 1929, the example is that of a glass sign element having on or at its rear side color matter, preferably fused to the plate, in patches of different colors or contrasting appearance, with an additional patch at the

rear of one of those patches, contrasting with the one patch; so that a flasher at the rear alternately causing the sign to be seen from its light, or seen from reflected light at the front, causes intermittent appearance of the additional matter along with the constantly appearing first mentioned patches, producing the illusion of animation. My present invention differs from my prior one just described in having, as one of the first mentioned patches, translucent sheet material of any desired color, at the rear of transparent sheet material bearing what answers to the description of the other one of the first mentioned patches, above; the translucent sheet having on its rear what corresponds to the additional patch as above described. The variation, therefore, from my prior patent, is not such as to depart from its principle, but is dictated by the nature of use of my present invention, that of a store, show window or bill board display, or the like; whereas the example emphasized in my prior patent is a ceramic product intended for that kind of display best recognized as similar to the filling station signs, and for which is adapted and affords an improvement, due to animation. In my present invention, my sign, of the principle just described, is constructed, preferably, of lighter materials, is produced by painting or printing the displays on the materials, and translucency is attained by selecting a translucent material for one of the elements; and the material is such as to permit the provision for changeability of part of the display to be integral with one of these elements.

I have chosen a simple example illustrating animation of a figure and intermittent display of reading matter; the two stages being indicated in Figs. 1 and 2. In Fig. 1 the transparent element 1 is viewed from the front by exterior lighting, displaying the representation 2 of a man's head and shoulders, and above this reading matter 3 and below this reading matter 3', all of which is a coating of suitable translucent color, such as paint, ink or the like, on the rear of the sheet or element 1. It is this sheet that bears the changeable reading matter 4 and 5, in a manner afterward to be described.

In Fig. 2 is shown the same sign viewed from the front by light from behind the display elements as well as from the exterior lighting, which latter now becomes relatively 5 of little effect, so that the saluting hand 6 of the man is represented, and the additional reading matter 7, at the right of the figure, also appears.

As all of the display material, except the 10 changeable matter 4 and 5, is on the backs of the sign elements, it is, in both Fig. 1 and Fig. 2, indicated by dotted lines; that appearing in both stages being represented by long dots, while in Fig. 2 the additionally appearing 15 matter is represented by very short dots. It will be understood, however, that in either stage, the actual appearance would be full lines and shades as in any sign, and that the colors may be black and white, or shades of 20 gray, as well as the other colors, so long as they contrast with the color of the translucent rear element 8, which may be of any desired color answering to the requirements as to contrast, just mentioned. Also, the front element 25 1 may be of any desired color, so long as it is transparent. The most suitable material for both elements is xylonite, or, as it is usually called, celluloid; this material being readily obtainable in a great variety of colors, 30 and either transparent or translucent.

The intermittent rear lighting is obtained by an incandescent lamp 9 (Fig. 3) with the switch 10, which represents some automatic device, such as the well known thermally acting "flasher" plug.

The backs of the elements are shown in Figs. 5 and 6, where all display matter is indicated in full lines, except the changeable matter 4 and 5, which is on the front of the 40 element 1 as before mentioned. The element 1 will be seen to bear merely what is seen in the stage of Fig. 1 when the sign is lighted from the exterior only; and the element 8, which is understood to be translucent whereas 45 the element 1 is transparent, is seen to have on its back the hand 6, the reading matter 7, as well as small details 2' of the features of the man, which, as is well known by artists, may be arranged to alter the expression of the face 50 of the man, as for example to the more smiling expression in Fig. 2 as compared with that in Fig. 1.

The changeable matter 4 and 5 consists of 55 separate transparent letters 11 and 12 (Fig. 7) held to the front of the element 1 by small tabs 13 formed by cutting the element 1 and bending the small portions left attached by the cuts; these tabs 13 which hold the letters 11 of the upper line of matter 4 are V-shaped, 60 whereas the tabs 13' of the lower line 5 are semicircular. In Fig. 8 the tabs 13'' are of approximately oblong shape, the elongation being in the horizontal direction of the reading matter; and in Fig. 9, instead of the tabs, 65 the element 1' is not cut, but strips 14 and 15

are attached to the front of the sheet, above and below, made of the same transparent material as is the element 1'. In any of these examples, the letters or other characters, as 70 the letters 11 of the upper line 4, or the letters and figures 12 of the lower line 5, or the letters 11' of Fig. 8, or the letters 11'' of Fig. 9, have such of their edge portions slipped behind the tabs or strips as may be presented therefor. For this reason, the tabs 13, 13' or 13'' are 75 provided at frequent intervals, preferably as closely as will not unduly weaken the structure of the element 1, so that a sufficient number of edge portions of each character will be caught by tabs, whatever position the characters may be brought to along the line, in accordance with the desired adjusting and spacing of the characters. The element 1 and the changeable characters will be understood 80 to be actually of very thin material.

The elongation of the tabs along the line of display, in Fig. 8, insures ample holding contact with the variously placed characters; and in Fig. 9 the continuous strips 14 and 15 85 of course provide contact anywhere within the range of the display. The tabs 13, 13' or 13'' are preferable to the strips 14 and 15, however, in that they are more economically produced; being integral with and worked out from the element 1. Also uniformity in 90 transparency of the element 1 and the tabs is better insured than where separate pieces are attached. Such attachment, with cement such as is used for such materials, and with the strips 14 and 15 cut from the same sheets 95 as the element 1, will allow practicable uniformity in transparency and color. Usually the element 1 and its tabs or strips are clear, leaving the color effects to the translucent element 8. The display matter, including the 100 removable and changeable characters 11, 12, 11' or 11'', which latter are preferably transparent, also may be of any desired colors. By having uniform transparency and color 105 of the element 1 or 1' and the tabs or strips, the latter are practically invisible in the display, either from front exterior or rear interior lighting. The illustrations in Figs. 7, 8 and 9 do not show this effect, as they are 110 made to show the construction, rather than the effect, which is more as shown in Figs. 1 and 2, with respect to the changeable characters. By having the tabs of proper close spacing they serve to hold the characters 115 properly at any required spacing, as is evident in Fig. 7.

The assemblage of the sign is best seen in Fig. 4, where the elements and display matter are numbered to correspond with Figs. 1 and 2, and are held between two clear transparent glass plates 16 and 17, which are held together by a frame 18 which may be opened for access to change the display matter 4 and 5.

Modifications may occur in practice, and 130

therefore, while I have specifically described preferred examples of my invention, I do not wish to be understood as being limited to such precise disclosure, but what I claim as new and desire to secure by Letters Patent is:

5 1. A sign comprising a transparent element and a translucent element behind said transparent element, sets of display matter contrasting with said translucent element, one set of which is in front and the other set of which is in back of said translucent element, at least part of one of said sets being removably mounted on one of said elements whereby it is changeable, and means for intermittently illuminating the rear of said elements and display matter.

10 2. A sign comprising a transparent element and a translucent element behind said transparent element, sets of display matter contrasting with said translucent element, one set of which is in front and the other set of which is in back of said translucent element, at least part of the front set being removable and changeable, and means for intermittently illuminating at the rear of said elements and display matter.

15 3. A sign comprising a transparent element and a translucent element behind said transparent element, sets of display matter contrasting with said translucent element, one set of which is in front and the other set of which is in back of said translucent element, at least part of the front set being removably mounted upon said transparent element whereby it is changeable, and means for intermittently illuminating at the rear of said elements and display matter.

20 4. A sign comprising a transparent element and a translucent element behind said transparent element, sets of display matter contrasting with said translucent element, one set of which is in front and the other set of which is in back of said translucent element, at least part of the front set being removably mounted on the front of said transparent element whereby it is readily accessible and changeable, and means for intermittently illuminating at the rear of said elements and display matter.

25 5. A sign comprising a transparent element and a translucent element behind said transparent element, sets of display matter contrasting with said translucent element, one set of which is in front and the other set of which is in back of said translucent element, said transparent element having engaging means uniformly transparent with said element, at least part of the front set of display matter being removably held by said engaging means whereby it is changeable, and means for intermittently illuminating at the rear of said elements and display matter.

30 6. A sign comprising a transparent element and a translucent element behind said transparent element, sets of display matter con-

trasting with said translucent element, one set of which is in front and the other set of which is in back of said translucent element, said transparent element having at its front engaging means uniformly transparent with said element, at least part of the front set of display matter being removably held by said engaging means on said front of said transparent element, whereby said part of said display matter is changeable, and means for intermittently illuminating at the rear of said elements and display matter.

7. A sign comprising a thin resilient transparent element and a translucent element juxtaposed to said transparent element, sets of display matter contrasting with said translucent element, one set in front and the other set in back of said translucent element, said transparent element having engaging means integral with and uniformly transparent with said transparent element, at least part of one set of said display matter being removably held by said engaging means whereby it is changeable, and means for intermittently illuminating at the rear of said elements and said display matter.

8. A sign comprising two juxtaposed elements, one transparent and the other translucent, sets of display matter contrasting with said translucent element, one set in front and the other set in back of said translucent element, said transparent element having engaging means uniformly transparent with said transparent element, at least part of one of said sets of display matter being removably held by said engaging means whereby it is changeable, and means for intermittently illuminating at the rear of said elements and said display matter.

9. A sign comprising a relatively thin resilient transparent sheet having substantially parallel rows of tabs integral with and uniformly transparent with said sheet, the tabs in each row projecting toward the other row, display matter removably and changeably held by said tabs, and illuminating means at the rear of said display matter.

10. A sign comprising a relatively thin resilient transparent sheet, engaging means on said sheet uniformly transparent with said sheet, display matter removably and changeably held by said engaging means, relatively thick transparent plates between which said sheet and said display matter are held, separable means for supporting said plates, permitting access to said display matter, and illuminating means at the rear of said display matter.

11. A sign comprising a relatively thin resilient transparent sheet having substantially parallel rows of tabs integral with and uniformly transparent with said sheet, the tabs in each row projecting toward the other row, display matter removably and changeably held by said tabs, a translucent element juxta-

- posed to said sheet, sets of display matter contrasting with said translucent element, one set in front of and the other set in back of said translucent element, means for holding said transparent sheet, said removably held display matter and said translucent element closely together, and means for intermittently illuminating at the rear of said translucent element.
10. 12. A sign comprising two juxtaposed relatively thin sheets, one transparent and the other translucent, sets of display matter contrasting with said translucent sheet, one set on said transparent element for display alone by light from the front of said sheets, and the other set in back of said translucent sheet for display with said one set by light from the rear of said sheets, relatively thick transparent plates between which said sheets and display matter are held, means for supporting said plates, and means for intermittently supplying said light from the rear of said sheets, display matter and plates.
